UNITED STATES PATENT OFFICE

WERNER MECKLENBURG, OF MOSCOW, UNION OF SOVIET SOCIALIST REPUBLICS, AS-SIGNOR, BY MESNE ASSIGNMENTS, TO KREBS PIGMENT AND COLOR CORPORATION, OF NEWARK, NEW JERSEY, A CORPORATION OF DELAWARE

PRODUCTION OF TITANIUM DIOXIDES

No Drawing. Original No. 1,758,528, dated May 13, 1930, Serial No. 236,918, filed February 1, 1930, and in Czechoslovakia May 5, 1928. Application for reissue filed April 12, 1932. Serial No. 604,861.

This invention relates to a process for the production of titanium dioxide by the hydrolysis of titanium salt solutions.

When titanium salt solutions such as the sulfate or chloride are heated to a temperature near the boiling point, hydrolysis occurs and a precipitate of TiO_2 is formed. At the same time, the acidity of the mother liquor is increased on account of the formation of additional free acid.

Dilute solutions of hydrolyzable titanium salts such as the sulfate or chloride are more easily hydrolyzed than concentrated solutions, but at the same time the economical production of titanium dioxide by this process requires the use of fairly concentrated salt solutions since, otherwise, the free acid obtained as a byproduct is too dilute to permit recovery and reconcentration.

In previously developed hydrolysis processes various plans have been advanced for conducting the operation in concentrated solutions. For example, hydrolysis has been effected by boiling the solutions at atmospheric pressure, in vacuo, and at elevated pressure. In other processes, hydrolysis has been accomplished by diluting a hot very concentrated solution with water or with mother liquor from previous hydrolyses.

Whenever titanium salt solutions are subjected to hydrolysis, a certain "lag" or induction period is observed between the commencement of the operation and the first visible precipitation, and it is believed that during this induction period, colloidal particles of TiO_2 are formed in the solution; which particles serve as centers for the accumulation of additional hydrolyzed particles and result in the formation of aggregates which produce a visible precipitate. In view of this explanation of the hydrolysis reaction, one might expect that the addition of TiO_2 produced by hydrolysis to a solution to be hydrolyzed would hasten the reaction. It has been found, however, that TiO_2 —produced by the ordinary hydrolysis reaction, whether colloidal or not—does not produce the desired seeding action.

I have now discovered a process for preparing a special form of titaniferous mate-

rial which, when added to a concentrated heated titanium salt solution such as the sulfate or the tetrachloride will produce a rapid and complete hydrolysis. One aspect of the invention deals with the production of this special material, hereinafter called "seed suspension". Another aspect of the invention relates to the use of said suspensions in the hydrolysis process.

By neutralizing a titanium solution, such as is used for hydrolysis, with sodium hydroxide, using methyl orange or bromphenol blue as an indicator, an aqueous mixture comprising a sodium salt solution and a suspension of titanium hydroxide is formed. If this mixture is maintained at an elevated temperature, in the neighborhood of 100° C., for a few minutes, some change in properties, not well understood, occurs and the resultant material may be used as a seed suspension for hydrolysis.

If a small amount of such a seed suspension is added to a hydrolyzable titanium solution, the mixture will appear turbid unless or until the temperature of the mixture is raised above 50–60° C. At about this temperature the turbidity disappears, the titanium hydroxide apparently dissolving in the solution. If the titanium solution, thus seeded, is maintained at about 100–105° C. for three hours the titanium content is almost entirely precipitated as TiO_2 , the yield of this material being in excess of 95%. Under the same conditions, an unseeded solution yields no more than 35–70% of TiO_2 . As little as 1% of seed (based on the weight of seed TiO_2 as compared to precipitated TiO_2) is sufficient to produce the desired result. The seed suspension, once prepared, does not deteriorate even after months of standing.

The advantages of this method of hydrolysis over others known in the art are obvious. By means of this improvement, it is possible to completely hydrolyze concentrated titanium solutions without long hours of boiling (which invariably produces a relatively poor result), without treatment under pressure, and without diluting the solution to be treated with either water or mother liquor from a previous hydrolysis.

Now, having generally described the invention, specific illustrations of its use will be given. To conduct the hydrolysis it is first necessary to prepare the seed suspension. This is accomplished by combining sufficient normal alkali hydroxide with (for example) a titanium sulfate solution to reduce the hydrogen-ion concentration to a point within the range pH 4 to pH 4.5. Within 10 in this range, the titanium hydroxide is largely precipitated to form a suspension within the alkali sulfate solution formed as a by-product of the reaction.

When the requisite proportions of titanium 15 sulfate solution and normal alkali hydroxide solution have been determined, the seed suspension is prepared by stirring the two materials together at a temperature of about 74°-80° C. This mixture is then maintained at a temperature of about 80° C. for 20 from fifteen to thirty minutes. At the end of this treatment, the resultant seed suspension may be used for the hydrolysis of titanium sulfate solution or it may be set aside for future use. If the material is not 25 to be used immediately, the temperature should be promptly reduced to below 60° C. at the end of the heat treatment. This may conveniently be accomplished by adding an equal volume of cold water. Thus treated, 30 the seed suspension is converted to a stable form and may be stored for months without deterioration.

While a convenient method of producing 35 the seed suspension has been described, it should be understood that this example is merely illustrative and is by no means limiting. A suitable material may be prepared by other methods, the only requisite items 40 being that the titanium sulfate solution be reduced to the proper hydrogen-ion concentration and that the resultant material be heat-treated at 80-100° C. for fifteen to thirty minutes. In place of an alkali hydroxide, 45 such as the hydroxide of sodium, potassium, or ammonium, the alkaline carbonates may be employed to reduce the hydrogen-ion concentration of the titanium sulfate solution to the proper point.

50 When the seed suspension is introduced into cold titanium sulfate solution, no reaction of any sort is apparent. If it is introduced into a hot solution, the suspended titanium hydroxide apparently dissolves and 55 the mixture is not turbid. If the seeded titanium sulfate solution is maintained at 100-105° C. (this being slightly below the boiling point) for about three hours, the titanium is completely hydrolyzed to form 60 TiO_2 , the yield being in excess of 95%, and sometimes as high as 98%. The TiO_2 thus produced may be removed by filtration and the mother liquor may be concentrated and used again for the treatment of ore, or for 65 other purposes.

The amount of seed suspension used to promote hydrolysis may be varied as desired. As little as 1% of TiO_2 in the seed solution as compared to the TiO_2 in the titanium sulfate solution gives satisfactory results. 70 More may be used, but the addition of a greater quantity dilutes the mother liquor which it is desired to reconcentrate. In practice, the titanium hydroxide in the seed solution may be allowed to settle and some of the 75 clear liquor (containing soluble sulfates) may be decanted off. The more concentrated seed solution may then be employed in proportionate quantity.

As illustrative of the results obtained by 80 my improved method of hydrolysis, the following table of data obtained with certain variations of the process is submitted. In all of the cases mentioned, 400 cc. of titanium sulfate solution were mixed with 45 cc. of 85 seed suspension and the mixture was maintained at a temperature near the boiling point for three hours.

		Seed suspension			Hydrolysis yield of TiO_2			90
TiO_2	H_2SO_4	Age	Alkali	pH value	1 hr.	2 hrs.	3 hrs.	
200	438	24	NaOH	2.7	87.6	93.2	95.2	95.2
200	440	30	NaOH	3.7	90.6	94.5	96.1	96.1
210	460	0	NaOH	4.5	93.2	94.3	95.0	95.0
212	488	0	KOH	2.8	-----	95.0	96.8	96.8
208	502	72	KOH	2.8	-----	94.0	95.0	95.0
185	465	0	KOH	3.2	95.8	98.0	99.0	100
200	440	0	NH ₄ OH	4.3	91.2	95.9	97.0	100
200	456	48	NH ₄ OH	4.4	91.2	95.9	97.0	100

As previously indicated, the advantages to be gained by the improved hydrolysis process depend in part on the economic improvement afforded by operating with concentrated solutions. However, the invention is equally applicable and operative in the case of dilute solutions.

While I prefer to use seed suspensions 110 at a hydrogen-ion concentration of about 4-4.5 as previously specified, my invention is capable of a wider use, as is shown in the above tabulation. In working with suspensions of greater acidity than pH 4—e. g. 2.5-4.0 as shown in the tabulation—, great care must be exercised to cool the seed suspension to 60° C. immediately after the formation reaction and the period of heating should be short—i. e. about fifteen minutes. On the other hand, seed suspensions may be prepared at a hydrogen-ion concentration of pH 4.5-6.0 by slightly increasing the duration and temperature of heating.

From the character of the “seed”, which 125 is actually a suspension of titanium hydroxide produced at a point near neutrality, and from the behavior of the seed suspension when added to the solution to be hydrolyzed, it appears probable that the titanium hy-

120 130

- droxide is not actually dissolved on heating but is converted to some colloidal form which promotes the hydrolysis of titanium sulfate solutions. However, the result attained 5 differs from other hydrolysis processes which are apparently promoted by the formation of colloidal particles prior to actual precipitation in at least two important respects:
- 10 (a) The quantity of promotion material is much smaller;
 (b) The desired result is attained without diluting the solution.
- 15 While the explanation given appears reasonable, any and all theories and explanations of the process are disclaimed and for a matter of convenience the expressions titanium hydroxide and titanium oxygen compound are used herein to designate the 20 precipitate obtained by reducing the acidity of a titanium salt solution, at any stage of its preparation and without reference to its exact chemical composition.
- 25 I claim:
- 26 1. A composition comprising titanium hydroxide in aqueous suspension at a hydrogen ion concentration of about pH 2.5-6.0.
- 27 2. In a process of preparing a seed suspension for use in the hydrolysis of a titanium salt solution, the steps of mixing together a neutralizing agent and a titanium salt solution until precipitation of a titanium oxygen compound is effected and heating the 30 precipitate to about 80° to 100° C. for 15 to 35 30 minutes.
- 36 3. In a process of preparing a seed suspension for use in the hydrolysis of a titanium salt solution, the steps of mixing caustic soda and a titanium sulfate solution until precipitation is effected and heating the mixture to 40 about 80° to 100° C. for 15 to 30 minutes.
- 45 4. The process of preparing a seed suspension for use in the hydrolysis of a titanium salt solution, which comprises mixing together sufficient neutralizing agent and a titanium sulfate solution to precipitate a titanium oxygen compound and to reduce the acidity of the mixture to a hydrogen-ion 50 concentration of pH 2.5-6.0 and heating the precipitate to about 80° to 100° C. for 15 to 30 minutes.
- 55 5. A process for preparing a seed suspension which comprises reducing at elevated temperature the acidity of a titanium salt solution to a hydrogen-ion concentration of pH 2.5-6.0 and cooling the mixture to below 60° C.
- 60 6. The process of producing a seed for use in the hydrolysis of a titanium salt solution which comprises precipitating a titanium oxygen compound by reducing the acidity of a titanium salt solution and heating the precipitate formed under conditions such that 65 the precipitate when added in small amount to a hydrolyzable titanium salt solution followed by three hours heating to the boiling point produces a hydrolysis yield in excess of 70%, said conditions having been established by precipitating a titanium oxygen compound from a similar solution at various degrees of acidity, at various temperatures and maintaining said precipitate for various lengths of time at said temperatures and determining in each instance the effect of 70 such precipitated compounds upon the hydrolysis yield of a titanium salt solution.
7. In a process for the production of titanium dioxide the steps which comprise adding to a titanium salt solution a precipitated seed prepared separately and heating said mixture to produce hydrolysis, said seed comprising a titanium oxygen compound which dissolves on heating in said titanium salt solution.
8. In a process for the production of titanium dioxide the steps which comprise adding to a titanium salt solution a suspension of a precipitated seed prepared separately and heating said mixture to produce hydrolysis, said seed comprising a titanium oxygen compound which dissolves on heating in said titanium salt solution.
9. In a process for the production of titanium dioxide the steps which comprise adding to a titanium sulfate solution a suspension of a precipitated seed prepared separately and heating said mixture to produce hydrolysis, said seed comprising a titanium oxygen compound which dissolves on heating in said titanium sulfate solution.
10. In a process for the production of titanium dioxide, the steps comprising adding a titanium oxygen compound to a precipitated titanium salt solution and heating said mixture to effect hydrolysis, said titanium oxygen compound being at least partly soluble on heating in said titanium salt solution and being further characterized by having been prepared by a process which includes as one of its steps precipitation by the reduction of the acidity of a titanium salt solution by mixing it with a neutralizing agent.
11. In a process for the production of titanium dioxide, the steps comprising adding a precipitated titanium oxygen compound to a titanium sulfate solution and heating said mixture to effect hydrolysis, said titanium oxygen compound being at least partly soluble on heating in said titanium sulfate solution and being further characterized by having been prepared by a process which includes as one of its steps precipitation by the reduction of the acidity of a titanium sulfate solution by mixing it with a neutralizing agent.
12. In a process for the production of titanium dioxide, the steps comprising adding a precipitated titanium oxygen compound to

a titanium salt solution and heating said mixture to effect hydrolysis, said titanium oxygen compound being at least partly soluble on heating in said titanium salt solution, and being further characterized by having been prepared by a process which includes as one of its steps digesting a precipitated titanium oxygen compound in a slightly acid to neutral reacting, aqueous medium 10 at an elevated temperature for an appreciable length of time, but not long enough to render it completely insoluble in said titanium salt solution.

13. In a process for the production of titanium dioxide, the steps comprising adding a precipitated titanium oxygen compound to a titanium sulfate solution and heating said mixture to effect hydrolysis, said titanium oxygen compound being at least partly soluble on heating in said titanium sulfate solution, and being further characterized by having been prepared by a process which includes as one of its steps digesting a precipitated titanium oxygen compound in a slightly acid to neutral reacting aqueous medium 20 at an elevated temperature for an appreciable length of time, but not long enough to render it completely insoluble in said titanium sulfate solution.

14. In a process for the production of titanium dioxide, the steps comprising adding a precipitated titanium oxygen compound to a titanium salt solution and heating said mixture to effect hydrolysis, said titanium

35 oxygen compound being at least partly soluble on heating in said titanium salt solution and being further characterized by having been produced by maintaining for a short time at an elevated temperature the precipitate obtained by reducing the acidity of a titanium salt solution when mixing it with a neutralizing agent.

15. In a process for the production of titanium dioxide, the steps comprising adding a precipitated titanium oxygen compound to a titanium sulfate solution and heating said mixture to effect hydrolysis, said titanium oxygen compound being at least partly soluble on heating in said titanium sulfate 50 solution and being further characterized by having been produced by maintaining for a short time at an elevated temperature the precipitate obtained by reducing the acidity of a titanium sulfate solution when mixing it with a neutralizing agent.

16. A process for the production of titanium dioxide which comprises adding a mixture containing titanium hydroxide in aqueous suspension containing sodium sulfate to 60 a solution of titanium sulfate, and maintaining the mixture at a temperature near the boiling point.

17. In a process of hydrolyzing a titanium salt, the steps of reducing the acidity of a 65 titanium salt solution thereby precipitating

a titanium oxygen compound therefrom, mixing said precipitate with a titanium salt solution containing substantially more titanium than that added, and heating the mixture to effect hydrolysis.

18. In a process of hydrolyzing titanium sulfate, the steps of reducing the acidity of a titanium sulfate solution by mixing said solution with a neutralizing agent, thereby precipitating a titanium oxygen compound 75 therefrom, mixing said precipitate with a titanium sulfate solution containing more titanium than that added, and heating said mixture to effect hydrolysis.

19. In a process of hydrolyzing titanium sulfate, the steps of reducing the acidity of a titanium sulfate solution to a pH from 80 2.5-6.0 by mixing it with a neutralizing agent, whereby a titanium oxygen compound is precipitated, heating said precipitate to 85 about 80° to 100° C. for from 15 to 30 minutes, mixing said titanium oxygen compound with a titanium sulfate solution containing more titanium than that added, and heating the mixture to effect hydrolysis.

20. A process for the production of titanium dioxide which comprises mixing about one part of titanium dioxide in the form of an aqueous suspension of titanium dioxide in a solution having a hydrogen-ion concentration of pH 2.5-6.0 with one hundred parts of titanium dioxide in the form of a sulfate solution, and maintaining the mixture at a temperature near the boiling point.

21. A process for the production of titanium dioxide which comprises adding about one part of titanium dioxide in the form of an aqueous suspension of titanium dioxide in a sulfate solution having a hydrogen-ion concentration of pH 2.5-6.0 to one hundred parts of titanium dioxide in the form of a sulfate solution containing about 180 grams per liter of TiO_2 and 400 grams per liter of titratable acid, and maintaining the mixture at a temperature near the boiling point.

22. A process for the hydrolysis of a titanium sulfate solution which comprises adding sufficient alkali to a small portion of said solution to reduce the acidity to a pH 2.5-6.0 and to precipitate titanium hydroxide therein, heating said mixture to about 80° C. for 115 15 to 30 minutes, mixing said mixture with the rest of the titanium sulfate solution, and maintaining the mixture at a temperature near the boiling point.

23. A process for the production of titanium dioxide which comprises mixing an aqueous suspension containing titanium hydroxide at a hydrogen-ion concentration of about pH 2.5-4.5 with a solution of titanium sulfate and maintaining the mixture at a temperature near the boiling point.

24. A process for the production of titanium dioxide which comprises mixing an aqueous suspension containing titanium hydrox-

ide at a hydrogen-ion concentration of about pH 2.5-6.0 with a solution of titanium sulfate at a temperature below 50° C., heating the solution to near the boiling point and 6 maintaining it at this temperature.

25. A precipitated titanium oxygen compound which is soluble at an elevated temperature in a titanium sulfate solution containing 200 grams TiO_2 and 440 grams 10 H_2SO_4 free and combined with TiO_2 per liter, which compound, when added to a titanium sulfate solution, accelerates at elevated temperature the hydrolysis of said titanium sulfate.
- 15 26. A precipitated titanium oxygen compound which is soluble at an elevated temperature in a titanium sulfate solution containing 200 grams TiO_2 and 440 grams H_2SO_4 free and combined with TiO_2 per 20 liter, which compound, when added to a titanium sulfate solution, accelerates at elevated temperature the hydrolysis of said titanium sulfate and which is further characterized by having been produced by reducing 25 the acidity of a titanium salt solution by the addition thereto of a neutralizing agent.

In witness whereof, I affix my signature.
WERNER MECKLENBURG.

CERTIFICATE OF CORRECTION.

Reissue No. 18,790.

April 4, 1933.

WERNER MECKLENBURG.

It is hereby certified that error appears in the printed specification of the above numbered patent requiring correction as follows: Page 3, lines 104 and 105, claim 10, strike out the word "precipitated" and insert the same before "titanium" in line 104, of same claim; and that the said Letters Patent should be read with this correction therein that the same may conform to the record of the case in the Patent Office.

Signed and sealed this 23rd day of May, A. D. 1933.

M. J. Moore.
